[57] CLAIM

The ornamental design for a can carton, as shown and described.

DESCRIPTION

FIG. 1 is a perspective view of a can carton showing our new design;
 FIG. 2 is a top plan view thereof; the bottom plan view being a mirror image thereof;
 FIG. 3 is a front elevational view thereof;
 FIG. 4 is a rear elevational view thereof;
 FIG. 5 is a left side elevational view thereof; the right side elevational view being a mirror image thereof;
 FIG. 6 is a top plan view of a carton in unassembled condition; the bottom plan view being a mirror image thereof;
 FIG. 7 is a front elevational view of FIG. 6; the rear elevational view being a mirror image thereof; and,
 FIG. 8 is a left side elevational view of FIG. 6; the right side elevational view being a mirror image thereof.
 The dash lines represent tear lines.
 The phantom lines represent fold lines.
